UNITED STATES PATENT OFFICE.

GAYLORD W. BEEBE, OF CLAYTON, GEORGIA.

INKING DEVICE.

Application filed September 22, 1916, Serial No. 121,645. Renewed July 25, 1921. Serial No. 487,518.

To all whom it may concern:

Be it known that I, GAYLORD W. BEEBE, a citizen of the United States, resident of Clayton, county of Rabun, State of Georgia, have invented certain new and useful Improvements in Inking Devices, of which the following is a specification.

The object of my invention is to provide means for applying ink to the surface of a roll and while capable of various uses, is designed particularly as an attachment to the inking rolls of a check protector.

A further object is to provide an inking device of simple, compact construction which can be easily mounted on the wall or casing of a check protector or other machine where inking rolls are used, said device being provided with means for regulating the flow of ink to the rolls of the printing platen.

The invention consists generally in various constructions and combinations, all as hereinafter described and particularly pointed out in the claims.

In the accompanying drawings forming part of this specification,

Figure 1 is a vertical sectional view through a check protector with my improved inking device attached thereto.

Figure 2 is a detail view of the inking device removed from the machine.

Figure 3 is a plan view of the inking device.

In the drawing, 2 represents the base of the machine, having a top or cover 3. 4 is a shelf whereon the check, draft or other instrument to be marked or printed is placed. 5 is a mechanism for gripping the paper. 6 is a printing platen and 7 is a quadrant therefor. 8 and 9 are keys mounted to operate a rod 10 and the gear 11 for revolving the pinion 12 and gear 13 to move the carriage 14 on which the printing platen is mounted. I do not go into the details of construction of this machine in this application, as a portion of it corresponds to the construction of a well-known patented check protector and other features form the subject matter of an application for Letters Patent of the United States which I have already executed and filed, September 11, 1916, Serial No. 119,591.

The carriage has a bracket 15 wherein inking rollers 16 and 17 are mounted in position to contact with the curved surface of the platen and ink the figures or characters thereon. 17^a is a cup-shaped receptacle hav-

ing lugs 18 thereon and a pin 19 passing through said lugs and through similar ones mounted on the cover of the machine for supporting the receptacle thereon and allowing it to rock against the tension of a coiled torsion spring 20 that is mounted on the pin 19. The lower portion of the cup projects within an opening 21 and is provided at its lower end with a wheel 22 which bears on the surfaces of the rolls 16 and 17, being held in yielding contact therewith by the spring 20. The surface of this wheel is preferably provided with a series of corrugations and the edges are rounded slightly to allow the rolls to slide back and forth thereon with the movement of the carriage without injury to the roll surfaces. Any other suitable form of wheel may be employed or a brush may be provided for bearing on the surfaces of the inking rolls.

The ink receptacle is provided with a lower or secondary inking chamber 23 having a passage leading to the corrugated wheel and a pad 24 arranged in said passage to bear on the surface of the wheel and spread the ink thereon. This pad is made preferably of a suitable fibrous material, which may be firmly pressed together to retard the flow of ink therethrough or may be made open and porous to permit the free flow of the ink according to the degree of feed desired, and the pad is preferably held against the surface of the wheel with a yielding pressure by the compression spring 25. 90 This spring is arranged in the lower inking chamber seated at one end on the pad and at its upper end on the upper wall of the chamber. The upper part of the receptacle comprises a sight glass 26 secured by screws 27 and having a suitable cap or cover 28. Within this sight glass is the main inking chamber 23^a, wherein a quantity of ink is maintained. The bottom of this chamber has a port 29 leading to the chamber 23 and through 100 which port the ink is permitted to flow to the inking pad beneath. A valve seat is provided around the port 29 for a needle valve 30 which is mounted in the top 28 and exteriorly threaded to engage a threaded 105 opening in said top, and is preferably provided with a lock nut 31 by means of which the valve may be adjusted in any desired position for regulating the feed of ink and locked in such position until such time as 110 it may be desired to change the feed.

I prefer to provide an air passage 32 in

the needle valve 30 for admitting air to the inking chamber 23 and preventing the formation of a vacuum therein. The cover 28 is provided with a suitable air port and 5 with a filling opening 33 having a cover 34.

In using the device, the receptacle is filled with ink and the valve adjusted to deliver the desired quantity of ink to the secondary chamber. From there the ink will feed 10 downwardly through the inking pad to the wheel or brush beneath, the density of the pad regulating the feed, which will also be governed to a considerable degree by the pressure of the spring above. As the inking 15 rolls are revolved, they will contact with the wheel and be thoroughly inked, and as the carriage supporting the platen is moved back and forth, the ink will be distributed from end to end of the rolls.

20 The receptacle as described is mounted to yield or rock on its support, so that the inking wheel will be held with a yielding pressure against the rollers. With this device the feed of the ink can be controlled 25 to a nicety and the proper supply maintained on the inking wheel to insure the even distribution on the inking rollers under all conditions.

In using the device, the upper or main 30 ink chamber may be used as a reservoir to supply the smaller lower chamber with ink from time to time, as needed. In this case the needle valve will be closed after the lower chamber is filled and kept in a closed 35 position until the lower chamber is empty and the operator of the machine desires to fill it again. In this way the ink is prevented from accumulating and drying on the valve seat, which it might do if the 40 needle valve should be normally left open. Furthermore, there will be less weight of ink on the pad 24 when the valve is closed and the rapidity of the feed slightly reduced.

45 I have shown and described this inking device applied to the mechanism of a check protector, but it may be utilized for feeding ink for other purposes, if desired.

In various ways the details of construction 50 herein shown and described may be modified and still be within the scope of my invention.

I claim as my invention:

1. The combination, with an inking device, of an ink receptacle, an ink distributing member for contacting with said inking device, a pad having means for yieldingly holding it against said ink distributing member and means for regulating the feed 60 of ink from said receptacle to said pad.

2. The combination, with the inking rolls, and a cover therefor provided with an opening adjacent to said rolls, of an ink receptacle hinged on said cover and having an 65 upper and a lower chamber, an ink dis-

tributing member communicating with said lower chamber, a pad mounted to contact with said member and through which the ink is fed from said lower chamber, and a valve for regulating the feed of ink from 70 the upper chamber to said lower chamber.

3. The combination, with the inking rolls and a cover therefor, of an ink receptacle mounted on said cover and having upper and lower ink chambers, an ink pad communicating with said lower chamber and through which the ink is fed to said inking rolls, there being a port provided between said upper and lower chambers and a valve for regulating the flow of ink from 80 said upper chamber to said lower chamber.

4. The combination, with the inking rolls and a cover therefor provided with an opening adjacent to said rolls, of an ink receptacle hinged on said cover and provided 85 with an inking wheel for contact with said rolls through said opening, a spring normally under tension for holding said receptacle and wheel in yielding engagement with said rolls, said receptacle having a 90 port for feeding the ink therethrough to said wheel, and means for regulating the delivery of the ink to said wheel.

5. The combination, with the inking rolls and a cover therefor, of an ink receptacle 95 mounted on said cover and provided with an inking wheel for contact with said rolls through said cover, an ink distributing member for contacting with said inking wheel, and means for regulating the feed of 100 ink from said receptacle to said member.

6. The combination, with a machine casing having an opening in its wall, of an ink distributing device adjacent said opening, and an ink receptacle hinged on said casing 105 and having an ink delivering material for contacting with said ink distributing device through said opening.

7. The combination, with a machine casing, of an inking wheel mounted therein and 110 inking rolls for contacting with said wheel, of an ink receptacle hinged on said casing and having an absorbent material for contacting with said inking wheel, and a valve mounted to regulate the flow of ink from 115 said receptacle to said absorbent material.

8. The combination, with a machine casing having an opening in its walls, of an inking wheel, inking rolls mounted to contact with said wheel, and an ink receptacle 120 hinged on said casing and having an absorbent material for contacting with said wheel through the opening in said casing.

9. The combination, with an inking roll and a casing therefor having an opening 125 opposite and adjacent said roll, of an ink receptacle mounted on said casing, an ink distributing device carried thereby for contact with said inking roll through said opening, means for holding said ink distributing 130

- device in contact with said roll with a yielding pressure, and means for regulating the delivery of ink from said receptacle to said distributing device.
- 5 10. An inking device comprising an ink receptacle having a discharge port and a chamber communicating with said port, a needle valve for closing said port having a duct therein communicating with said 10 chamber, a pad of absorbent material mounted to receive the ink from said chamber, and an ink distributing device mounted to contact with said pad.
- 10 11. An inking device comprising an ink receptacle having a discharge port and a valve for said port and a chamber communicating with said port, a pad mounted to receive the ink from said chamber, a distributing wheel contacting with said pad, 15 a spring for normally holding said pad in contact with said wheel, the movement of said valve regulating the flow of ink from said receptacle to said chamber.
- 15 12. The combination, with a machine having inking rolls, of an ink receptacle hinged on said machine, an ink distributing device mounted in said ink receptacle for contact with said rolls, a spring for normally holding said ink distributing device in yielding 20 engagement with said rolls, said ink receptacle having a discharge port and a valve for regulating the flow of ink through said port to said ink distributing device.
- 20 13. An inking device comprising an ink receptacle having a discharge port, a pad of absorbent material mounted to receive the ink from said port, an ink distributing roller mounted to contact with said pad and inking rollers mounted to contact with said ink 25 distributing roller.
- 25 14. In combination, with the printing dies, inking rollers mounted in the path of said dies for contact therewith, a hinged ink distributing device arranged to contact with said rollers, an ink receptacle adapted to contain a supply of ink and means mounted to receive the ink from said receptacle and deliver it upon the surface of said ink distributing device.
- 30 15. The combination, with inking rollers and frame wherein they are mounted, an ink receptacle hinged on said frame and yielding held toward said rollers and having a chamber to receive a supply of ink, an ink distributing device carried by said receptacle and adapted to receive ink from said chamber, and said ink distributing device being held with a yielding pressure against said inking rollers.
- 35 16. The combination, with a machine casting and an ink roller mounted therein and printing dies for engagement with said roller, of an oscillating ink receptacle adapted to contain a supply of ink and held toward said inking roller with a yielding pres-
- sure, an ink distributing device mounted to receive ink from said receptacle and contacting with said inking roller.
- 40 17. An inking device comprising an ink receptacle having a discharge port, a pad of absorbent material mounted to receive the ink from said port, an ink distributing roller mounted to contact with said pad, an inking roller and printing dies therefor arranged to contact with said ink distributing device, and means for holding said ink distributing device in contact with said roller with a yielding pressure.
- 45 18. The combination, with a machine frame, of an inking device pivoted thereon and comprising an ink receptacle, an ink distributing device mounted to receive the ink from said receptacle, an inking roller and means yieldingly holding said distributing device in contact therewith, and printing dies mounted to contact with said inking roller.
- 50 19. An inking device comprising an ink receptacle having a discharge port, a pad of absorbent material mounted to receive the ink from said port, an ink distributing device mounted to contact with said pad and comprising a roller having a plurality of longitudinal peripheral grooves, and inking rollers mounted to contact with said ink distributing device.
- 55 20. An inking device comprising an ink receptacle having a discharge port, a pad of absorbent material mounted to receive the ink from said port, an ink distributing device mounted to contact with said pad and comprising a metallic roller having a plurality of peripheral grooves for contact with said pad, and inking rollers mounted to contact with said ink distributing device.
- 60 21. An inking device comprising an ink receptacle having a discharge port, a pad of absorbent material mounted to receive the ink from said port, an ink distributing device mounted to contact with said pad and comprising a metallic roller having rounded or beveled ends and provided with a plurality of longitudinal peripheral grooves, and inking rollers mounted to contact with said ink distributing device.
- 65 22. An inking device comprising an ink receptacle having a depending hollow stud, an ink distributing roller mounted in the lower portion of said stud, means arranged in said hollow stud for receiving the ink from said receptacle and delivering it to the surface of said ink distributing roller, means for pivotally mounting said receptacle on a machine casing, and inking rollers arranged to contact with said ink distributing roller.
- 70 23. An inking device comprising an ink receptacle having a discharge port, an ink distributing device mounted to receive ink from said port and comprising a roller having rounded or beveled ends and provided

with a plurality of longitudinal peripheral grooves and inking rollers mounted to contact with said ink distributing device.

24. An inking device comprising an ink receptacle having a discharge port, a distributing device mounted to receive ink from said receptacle and comprising a roller

having a plurality of longitudinal grooves, and inking rollers mounted to contact with said distributing device.

In witness whereof, I have hereunto set my hand this 18th day of September, 1916.

GAYLORD W. BEEBE.
